UNITED STATES PATENT OFFICE.

RALPH T. BRASWELL AND OREN M. FLANDERS, OF MIAMI, FLORIDA.

RAILWAY-CROSSING SIGNAL.

Application filed September 12, 1927. Serial No. 219,111.

This invention relates to railway crossing signals and has for an object to provide a signaling device stationed at a position adjacent the crossing and provided with electrical signaling means operatively connected through the rails of the track with a source of energy mounted on the train so that upon the approach of the train upon a certain predetermined section of the track the signal will be automatically operated.

A further object is to provide a novel means for transmitting the current from the source of energy carried by the train to the signal and comprising a trolley rail arranged between the rails of the track and disposed in contacting position with a trolley wheel mounted on the train, said trolley wheel being electrically connected with the source of energy so that upon the approach of the train to a predetermined section of the track, an electrical connection will be made between the signal and the source of energy by reason of the engagement of the trolley and trolley track.

25 A further object is to utilize the source of current generally provided for the electric lighting system of the train for the operation of the crossing signal.

30 A still further object is to provide means for yieldably mounting the trolley wheel upon the train whereby to produce a positive contact between the trolley wheel and the trolley track at all times, whereby to insure a proper connection for the operation of the signal during the traveling of the train over the signaling section of the track.

35 An additional object is to arrange a section of the trolley track at opposite sides of the railway crossing so that the signal will be operated upon the approach of trains from either direction.

40 Another object is to provide an apparatus of this character of simple and practical construction, efficient and reliable in performance, relatively inexpensive to manufacture, and install, and otherwise well adapted for the purposes for which it is intended.

45 Other objects and advantages reside in the special construction and combination of the various elements forming the invention, reference being had to the accompanying drawings forming a part hereof, wherein:

50 Figure 1 is a plan view of a section of railway track at a highway crossing showing the signal in position with respect thereto.

55 Figure 2 is a diagrammatic view showing the circuit between the train and the signaling device.

60 Figure 3 is an elevational view of the signal.

65 Figure 4 is a vertical sectional view taken along a line 4-4 of Figure 3 showing the signaling elements mounted within the signal box.

70 Figure 5 is a fragmentary sectional view taken along a line 5-5 of Figure 3.

75 Figure 6 is a vertical sectional view through the signaling arm taken along the line 6-6 of Figure 3.

80 Figure 7 is an elevational view of the forward end of a locomotive illustrating a practical manner of mounting the trolley wheel thereon, and operatively connecting the same with a source of power.

85 Figure 8 is a bottom perspective view of one end of the trolley track.

90 Figure 9 is a perspective view of one of the supports therefor.

95 Figure 10 is a similar view of the angular bracket for supporting the trolley wheel.

100 Figure 11 is a transverse sectional view through a section of the railway equipped with the trolley track.

105 Figure 12 is a sectional view through the trolley and slidably mounting therefor, and,

110 Figure 13 is an elevational view of the guide channel for the trolley bracket showing its facing provided with spot babbittting designed to reduce friction between these parts.

115 Referring now to the drawings in detail, the invention comprises a trolley rail 5 arranged longitudinally between the rails 6 of a track, said trolley rail being mounted upon supports 7 anchored to the rail ties 8 and arranged so that the trolley rail will be elevated slightly above the track rails as shown in Figure 11.

120 The trolley rail preferably is of a channel shaped formation, opening downwardly and seated upon the upper end of the supports 7, the flanges 9 of the trolley rail being adapted to overlap the upper edge of the support. The ends of the trolley rail are inclined downwardly to the level of the upper face of the ties 8 and have attaching plates 10 formed at the ends thereof by means of which the same may be secured to the ties. In placing the invention in practice, a section of the trolley rail is arranged at opposite sides of a highway or other cross-

ing indicated at 11 for the purpose as hereinafter explained.

The trolley rail 5 is adapted to be engaged by a trolley wheel 12 rotatably mounted on a supporting bracket 13 having a vertically disposed channel shaped guide 14 adapted to slidably receive a bracket 15 which may be fixedly secured to any suitable part of a locomotive or other car 16, as for instance, upon the pilot 17 as shown in Figure 7. The bracket 15 is retained in slidable position within the channeled guides 14 by means of a plate 18 secured to the edges of the guide as by means of bolts 19 or the like. A horizontal extension 20 is angularly formed on the bracket 15 and a similar extension 21 is formed on the upper end of the guide 14 in parallel relation therewith and through which is inserted a bolt 22 with a coil spring 23 carried thereon and tensionally retained between the extensions 20 and 21. The tension of the spring 23 is adapted to normally force the trolley wheel 12 downwardly whereby to cause a positive engagement of the same upon the track 5.

The base of the channel formed in the guide 14 may be provided with recesses within which spot babbetting as indicated at 24 may be inserted whereby to reduce friction between the bracket 15 and the base of the channel of the guide 14.

At a position adjacent the crossing is arranged a signaling device comprising a base 25 upon which is fixedly mounted a mast 26 which may be of any suitable construction or design, and having a signaling arm 27 supported at its upper end as by means of brackets or clamps 28. A signaling box 29 is mounted on the upper outer end of the signaling arm 27, said box being of a substantially rectangular formation and having its opposite sides provided with suitable perforations to form signaling indicia as indicated at 30. The interior of the sides of the box provided with the signaling indicia carries a transparent plate 31 which may be of colored glass if desired, whereby the light from an electric light bulb 32 mounted in the base of the box may operate to illuminate such indicia.

An audible signalling device 33, which may be in the form of a bell, horn or other sound producing device is also mounted within the signaling box and together with the light 32 is electrically connected through wires 34 and 35 respectively with the trolley rail 5 and one of the track rails 6.

The trolley wheel 12 with its support 13 and bracket 15 is insulated from the locomotive or other car and constitutes an electric conductor being connected through wires 36 with a generator 37 mounted on the car and which is usually provided for supplying electric current to the lighting system of

the train. One of the connections with the generator is grounded as at 38 through the frame of the car whereby to complete the circuit with the track 6 through the car wheels.

In the operation of the device it will be apparent that as the train approaches the section of the track provided with the trolley rail 5, that upon contact therewith of the trolley wheel 12 the current from the generator 37 will be transmitted to the signal device whereby to operate as a warning of the approach of the train. The audible signaling device 33 will operate as a suitable signaling means during the daytime 80 and the same together with the light 32 will constitute an effective signal at night. As shown in Figure 1 of the drawing, a section of the trolley track 5 may be arranged at each side of the crossing provided with 85 the signal so that the signal will be operated upon the approach of trains from either direction.

The section of the track 6 forming the electrical connection with the signal should of course, be suitably insulated from the remaining track sections. The trolley rail may be of any suitable length whereby to regulate the length of time during which the signal will operate upon the passing of 95 a train and may be arranged at any desired distance from the crossing so that the signal will be actuated at the proper time depending upon the usual speed of the train traveling that particular section of the track and 100 with respect to the geographical conditions surrounding the crossing.

It is obvious that the invention is susceptible to various changes and modifications without departing from the spirit or scope 105 of the appended claims or sacrificing any of its advantages, and we accordingly claim all such forms of our device to which we may be entitled.

We claim:—

1. In a trolley wheel adapted to form an electric connection with a rail, comprising a fixedly mounted bracket, a support adapted to rotatably carry the wheel, a channel-shaped guide formed on said support and arranged to slidably receive said bracket, a plate removably carried by the guide whereby to retain said bracket within the guide, babbitt sections formed in the face of said guide arranged for frictional contact with said bracket, horizontal extensions formed at the upper ends of the brackets and the guide and yieldable means interposed therebetween whereby to normally urge said guide outwardly with respect to said bracket 115
2. A trolley wheel mounting comprising an L-shaped attaching bracket, a support for the trolley wheel having a groove formed therein providing a seat for slidably receiving the bracket, said groove having its base 120
3. A trolley wheel mounting comprising an L-shaped attaching bracket, a support for the trolley wheel having a groove formed therein providing a seat for slidably receiving the bracket, said groove having its base 125
4. A trolley wheel mounting comprising an L-shaped attaching bracket, a support for the trolley wheel having a groove formed therein providing a seat for slidably receiving the bracket, said groove having its base 130

inlaid with spot babbitt, a removable plate carried by the support arranged to retain the bracket therein, and spring means yieldably connecting the angular end of the bracket with the support, said bracket having a circuit wire attached thereon for transmitting an electric current picked up by con-

tact of the wheel with an electrified object disposed in the path thereof.

In testimony whereof, we affix our signatures.

RALPH T. BRASWELL.
OREN M. FLANDERS.
